HENRY C. SERGEANT, OF NEW YORK, N. Y.

Letters Patent No. 91,675, dated June 22, 1869.

IMPROVEMENT IN WATER-METERS.

The Schedule referred to in these Letters Patent and making part of the same.

To all whom it may concern:

Be it known that I, HENRY C. SERGEANT, of the city, county, and State of New York, have invented a new and useful Improvement in Water-Meters, and other motors, of which the following is a full, clear, and exact description, reference being had to the accompanying drawing, forming part of this specification, and in which—

Figure 1 represents a vertical longitudinal section of a water-meter constructed in accordance with my improvement;

Figure 2, a transverse section of the same, taken as denoted by the line $x-x$ in fig. 1; and

Figure 3, a horizontal section of the piston and cylinder of the meter, detached.

Similar letters of reference indicate corresponding parts.

My invention consists in such an arrangement of passages in the main piston, together with others connecting the main and valve-cylinders, in combination with a reciprocating main piston, working within a suitable cylinder or case, and an independently reciprocating valve, arranged to operate within an adjacent case or cylinder, as that on admitting the impelling-fluid to the valve-box or cylinder, and freely or continuously keeping open such admission, and maintaining in a like continuous manner an open character to the exhaust-passage from the main cylinder, an automatic reciprocating action is kept up of both the valve and main piston under a mutual control, the one by the other, without the intervention of tappet or other gear, or aid of an independent secondary valve.

Referring to the accompanying drawing—

A represents the cylinder of the meter, covered at its opposite ends by hollow cylindrical caps or heads, B B', of somewhat larger interior diameter than that of the cylinder.

Within or through this cylinder, and into the hollow heads B B', a piston, C, is arranged to work or reciprocate, said piston being shown as constructed of a double-bucketed or chainbered form, that is, having open-end chambers $a a'$ on opposite sides of a central diaphragm portion of the piston.

Said piston is also constructed or provided with diagonally-arranged passages or pipes D D', one on either side of its diaphragm; the same opening at their opposite ends, through the periphery of the chambers $a a'$, or oblique slots may be substituted for such passages.

E is the exhaust-passage of or to the cylinder A, the same being in direct communication, by an opening, b, with said cylinder or piston moving therein, and by an opposite opening or passage, b', with the valve-box or cylinder F, with which passages G G', leading to opposite ends of the cylinder A, also are in communication on opposite sides of the opening b'.

The valve-box or cylinder F has also end pipes or passages H H', connecting it with the cylinder A at points intermediate of the ends of said cylinder and exhaust-opening b thereto, and in line with the one end of either diagonal pipe D D'.

I is the water-inlet to the valve-cylinder F, and which is in communication, by passages c c', with the central or intermediate portion of said cylinder F.

Arranged to reciprocate within this cylinder, is a piston-valve, J, made up of extended end heads d d', and a central head, e, with reduced portions, f f', between the latter and the end heads.

The central head e is of slightly greater width than the exhaust-port or opening b', so as to establish lap on both sides of said opening in passing over it, while the inner faces of the end heads d d' are at such distance from each other as that when the central head e is over the exhaust-opening b', communication is established for the incoming water through the passages c c' to the cylinder F, between the central head e and both end heads d d'.

The operation is as follows:

Supposing the parts to be situated as represented in the drawing, water entering the cylinder F by the passages c c', exerts an opposite or counteracting tendency on the several heads of the valve that serves to impart no motion to the latter, and, were the pressure to be equal on the outer surfaces of the end heads, as well as on the inner faces thereof, the valve would remain stationary; but although, in the working of the meter, both the main and valve-cylinders and several passages are full of water, there, nevertheless, is established an inequality of pressure on the outer surfaces of the end heads d d', as the piston C reaches the end of its stroke in either direction, which inequality serves to throw the valve, and by so doing to reverse the motion of the piston. This is done by establishing communication, through the motion of the piston, between the cylinder F, alternately at its opposite ends, and the general exhaust E. Thus, as the parts stand, the piston C having reached the end of its stroke to the right hand, the pipe D is brought into communication, through the port b, with the exhaust E, and through the pipe H' with the right-hand end of the cylinder F, which causes the valve J to be thrown in direction of the arrow z, by reason of the pressure of the water received by the pipe H from the cylinder A acting against the back of the head d, while the outer face of the head d' is relieved from pressure by the communication of that end of the valve-cylinder with the exhaust through the pipes H' and D.

This shifting of the valve J to the right, prevents water being admitted through the passage c, and opens the exhaust-port b' to the passage G, which relieves the piston C of pressure on its left-hand side or face, while it is exposed on its opposite side or face to full

pressure of the incoming water, received through the passages *c* and *G*', which shoots the piston *C* to the opposite end of the cylinder. As the piston *C*, however, thus moves to the left hand, or as it approaches the end of such stroke, its pipe *D*' is brought into communication with the exhaust-port *b* and pipe *H*, and the pipe *H*' made to freely supply water to the back of the head *d*', which reverses the action or throw of the valve *J*, causing it, as it passes to the left hand, to again assume the position represented in the drawing, and, as the valve is thus thrown to the left, the passage *c* is closed by the head *d*', and passage *G*' opened to the exhaust-port *b*', and water freely received through the passages *c* and *G*. This causes the piston *C* again to be moved to the right, and in due course the valve to be again reversed.

In this way is a continuous reciprocating action kept up of the independent piston and valve without the aid of internal or external gear, the motion of either one being controlled by the movement of the other over its or their respective passages.

The lap given to the exhaust by the head *e*, and distances of the heads *d* *d*' apart relatively to the passages *c* *c*', prevent any dead-point in the throw of the valve, and it is desirable that the pipes *H* *H*' should never be entirely closed by the heads *d* *d*', so that there will always be water in the ends of the cylinder *F* to start the valve back again, and to secure for it a cushioning action, which latter may be enlarged by notching the heads *d* *d*', as at *s* *s*.

Though the valve *J* is here shown as of a balance cylindrical character, a different form of valve may be substituted, or a combination of flat slide-valve with end heads may be employed, if preferred.

It is also desirable to notch the ends of the chambers *a* *a*', as at *m* *m*, to insure a free ingress for the water to give a cushioning action to the piston *C*, and prevent it striking the hollow caps or heads *B* *B*' at the ends of its stroke.

To guide the piston *C* in a direct course, or keep it from turning and throwing its pipes *D* *D*' out of line with the passages *H*, *b*, and *H*', which they control, said piston may be provided with one or more eyes or hoops, *h*, that, as the piston reciprocates, is or are made to engage with a rod or rods, *i*, fast to either head *B* *B*'. This mode of guiding the piston renders unnecessary all objectionable rod-extension for the purpose, outside of either cap *B* or *B*'; also involves no leakage or packing.

The quantity of water passing through the meter

or out of the exhaust, each stroke of the piston, being ascertained by the capacity of the chambers *a* *a*', or quantity of water displaced by them, it only requires to connect the piston *C* with a suitable indicator to effect a perfect register. This may be done by an attachment, *k*, to the piston and connecting-devices running through the one end of the cylinder *A*, or otherwise.

The same combination of main piston with its cylinder, valve, and its cylinder and passages, as described, may be used in working the device as a motor to operate a pump, steam being substituted for water, as the impelling-fluid, to throw the piston and valve, and the piston being provided with a rod extending through either head *B* or *B*' of the cylinder, for the purpose of establishing connection of it with the plunger of the pump.

What is here claimed, and desired to be secured by Letters Patent, is—

1. A reciprocating piston and independent reciprocating valve, having passages connecting their respective cylinders or cases and water-ways in the piston, in connection with suitable inlet and outlet-passages, so arranged that the valve and piston are made to control each other by the direct action of the fluid passing through the meter, without the aid of valve-gear or other intervening mechanical devices, substantially as set forth.

2. The combination of the piston *C*, cylinder *A*, and hollow heads or caps *B* *B*', with the valve *J*, having heads *e* *d* *d*', and cylinder *F*, provided with passages *H* *H*', connecting the valve-cylinder with the main cylinder, and main inlet and outlet-passages *I* and *E*, essentially as shown and described.

3. The valve *J*, so constructed and arranged relatively to the exhaust-port *b*', which it controls, and inlet-passages *c* *c*', as that while said valve overlaps the exhaust-port in passing it, ingress is established for the impelling-fluid through the passages *c* *c*' to the valve and opposite ends of the main cylinder, substantially as described.

4. The combination, with the piston *C*, of one or more eyes or loops, *h*, and guide-rods *i*, arranged within the main cylinder or its heads, substantially as shown and described, for the purpose set forth.

H. C. SERGEANT.
